O. B. DAWSON.
CRUDE OIL BURNER.
APPLICATION FILED DEO. 15, 1910.

1,027,699.

Patented May 28, 1912.

UNITED STATES PATENT OFFICE.

OLIVER B. DAWSON, OF EL PASO, TEXAS.

CRUDE-OIL BURNER.

1,027,699.

Specification of Letters Patent. Patented May 28, 1912.

Application filed December 15, 1910. Serial No. 597,530.

To all whom it may concern:

Be it known that I, OLIVER B. DAWSON, of El Paso, in the county of El Paso and State of Texas, have invented certain new and useful Improvements in Crude-Oil Burners; and I do hereby declare the following to be a full, clear, and exact description of the invention, such as will enable others skilled in the art to which it appertains to make and use the same.

The primary object of this invention is to provide simple and highly efficient means for insuring the burning of the vapor or gas of crude petroleum mixed with heated air currents, whereby, within the fire box of a stove or range, complete combustion will be obtained with the total absence of smoke. And a further object of my invention is to provide an attachment which may be readily applied to stoves and ranges now in general use.

Briefly stated, I obtain the desired results by vaporizing the oil before it reaches the bottom of the gas producer, at which point it is flared out and is united, at the point of combustion, with columns of hot air, whereby an instantaneous and high temperature will be obtained.

The invention will be hereinafter fully set forth and particularly pointed out in the claims.

In the accompanying drawings, Figure 1 is a vertical sectional view of a stove equipped with my present invention. Fig. 2 is a transverse sectional view on line 2—2, Fig. 1. Fig. 3 is a plan view of the lower series of air tubes.

Referring to the drawings, 1 designates a reservoir which is designed to contain crude petroleum oil. This reservoir is removably supported by a sight feed chamber 2, which may be of any preferred form of construction, but which is preferably provided at its upper end with a tubular portion 2^a to receive the lower end of a pipe 3 depending from the reservoir, said pipe having on its exterior a flange or collar 4 which forms a stop for holding the reservoir immediately above the sight feed chamber from which it may be readily removed. Within pipe 3 is a pet cock 5 for controlling the flow of the oil. From the bottom of the sight feed chamber depends a tube 6 which extends down into the stove, conventionally shown at 7, to a point near the bottom thereof. I preferably form this tube 6 with a

flared flange 6^a at its lower end. According to my invention, the heat produced within the combustion chamber of the stove is intended to heat tube 6 to such a degree as to 60 volatilize the oil before it reaches the lower end of the tube. In order to insure contact of the oil with the heated wall of tube 6 I preferably locate in the latter, at a point near the top of the stove, an inclined deflector 9 in the form of a plate riveted or otherwise attached to the interior of tube 6 and extending transversely across part thereof, but not closing the latter.

Immediately beneath the lower flared end 70 of the vaporizing tube 6 I provide a series of air inlet tubes 10 which are preferably circularly arranged on a support 12, which latter extends entirely across the combustion chamber, preventing any air from 75 passing from the lower to the upper portion of the latter excepting through the air tubes 10. The latter are preferably deflected at their upper ends, at an angle of about 45°, as shown at 13, so as to direct the 80 flame upwardly and outwardly into the space surrounding the vaporizing tube, thus securing a uniform distribution of the heat throughout the fire-box or combustion chamber. These air inlet tubes project 85 above their support such a distance that they will be thoroughly heated by the burning gas or vapor, with the result that within a very short time after the vapor is lighted the air passing through tubes 10 will be 90 thoroughly heated. I find that by heating the air before it mixes with the oil gas complete combustion may be obtained within the fire box. The flame is drawn upwardly in 95 the fire box by chimney suction. In starting, a small quantity of oil is placed on support 12, which is preferably of pan shape, and surrounds the air inlet tubes 10 so that the heat generated by this initial supply of oil will not only heat the latter tubes, but 100 will heat tube 6 so as to vaporize the oil flowing against the heated wall thereof. For the purpose of supplying additional currents of heated air, and thus insuring complete combustion within the fire box, I 105 surround the vaporizing tube 6 with a series of down draft hot air tubes 15 which are supported at their upper ends by the top plates 16 of the stove, or it may be a separate plate set into the top of the stove, such pipes 110 15 at their lower ends opening in close proximity to the discharge end of the tube 6.

The heat within the fire box will thoroughly heat tubes 15 and fresh air passing downwardly through such tubes will be heated while in transit therethrough.

- 5 Any suitable means may be employed, for instance, a perforated plate 17, for holding tubes 15 in fixed relation to tube 6.

From what has been said it will be seen that no cold air is permitted to enter the 10 fire box; and that the air, whether it be introduced solely through the lower series of pipes 10 or in addition thereto through the series of pipes 15, will be thoroughly heated by the time it reaches the discharge end of 15 the vaporizing tube 6. In consequence, complete combustion will be effected, and smoke, after the stove has been well started, will be entirely eliminated.

I have shown a drip pan 20 beneath the 20 lower series of air tubes for collecting any oil or by-products that may in any way be allowed to pass through such air tubes.

I claim as my invention:—

1. The combination with a closed fire-box 25 having a chimney outlet, and an oil reservoir, of a vaporizing tube leading from the reservoir and depending into the closed fire-box, oil entering said tube being designed to be vaporized in its descent therethrough, 30 a series of hot air tubes circularly arranged relatively to the lower end of the vaporizing tube, said hot air tubes opening at their upper ends toward the upper end of the fire-box, and an imperforate support for 35 said hot air tubes for preventing air from passing into the fire box other than through said hot air tubes.

2. The combination with a closed fire-box having a chimney outlet, and an oil reservoir, of a vaporizing tube leading from the reservoir and depending into the closed fire-box, oil entering said tube being designed to be vaporized in its descent therethrough, a 40 series of hot air tubes beneath the lower end 45 of the vaporizing tube, said hot air tubes being upwardly and outwardly deflected at their upper ends to direct the flame at the lower end of the vaporizing tube upwardly in the fire-box, and an imperforate support 50 for said hot air tubes.

3. The combination with a closed fire-box having a chimney outlet, and an oil reservoir, of a vaporizing tube leading from the reservoir and depending into the closed fire-box, oil entering said tube being designed to 55 be vaporized in its descent therethrough, a series of hot air tubes beneath and surrounding the lower end of the vaporizing tube, an imperforate support for said hot air tubes, and a second series of hot air tubes surrounding said vaporizing tube and opening at their lower ends at or near the lower end of said vaporizing tube, said second series of hot air tubes being open to the atmosphere at their upper ends. 60

4. The combination with a stove having a closed fire-box and a chimney outlet, and an oil reservoir, of a vaporizing tube leading from the latter and depending into the closed fire-box, the oil entering said tube being designed to be vaporized in its descent therethrough, a deflector within said vaporizing tube at a point near the upper end thereof, a series of hot air tubes beneath the lower end of said vaporizing tube, said hot air tubes opening upwardly and outwardly at their upper ends, and an imperforate support for said hot air tubes. 70

5. The combination with a stove, and an oil reservoir, of a vaporizing tube leading 80 from the latter and depending into the upper portion of the fire box within said stove, a deflector within said vaporizing tube near the upper portion of the fire box, a series of hot air tubes beneath the lower end of said 85 vaporizing tube, a support for said hot air tubes dividing the fire box into upper and lower portions, and a second series of hot air tubes surrounding said vaporizing tube and leading from the top of the fire box and 90 opening at their lower ends around the lower end of the vaporizing tube. 90

In testimony whereof, I have signed this specification in the presence of two subscribing witnesses:

OLIVER B. DAWSON.
